UNITED STATES PATENT OFFICE.

CHARLES C. STUART, OF CAMPVILLE, CONNECTICUT, ASSIGNOR TO
CRESWELL & WATERS CO., A CORPORATION OF PENNSYLVANIA.

SANDPAPERING-MACHINE PAD.

SPECIFICATION forming part of Letters Patent No. 738,956, dated September 15, 1903.

Application filed October 24, 1902. Serial No. 128,650. (No model.)

To all whom it may concern:

Be it known that I, CHARLES C. STUART, a citizen of the United States, residing at Campville, in the county of Litchfield and State of Connecticut, have invented certain new and useful Improvements in Sandpapering-Machine Pads, of which the following is a specification.

My invention relates to sandpapering-machines, and has for its object the combined use of abrasive rotary drums and abrasive reciprocating pads for finishing the stock or material passed thereunder upon the machine's platen or bed, together with means whereby the pads are reciprocated by mechanism attached to the machine and a part thereof driven by the same power. The pads are also provided with independent means, whereby they may be separately employed or put out of employment. It is designed to provide the pads with fine sandpaper for finishing the work and to employ the one for such purpose which the stock is passed under after it has passed under the drums which are coated with coarse, medium, and fine sandpaper, in the order named, which also indicates the course of the stock through the machine when being finished.

My mechanism is illustrated in the accompanying drawings, in which—

Figure 1 is a side elevation of so much of the machine as is necessary to illustrate the mechanism. Fig. 2 is a partial plan or top view showing a portion of the parts, as the pad-driving mechanism of one side, for its reciprocation, and the pad relative position to the drums. The parts of the driving mechanism not shown (for the opposite side of the machine) are duplicates of those shown, and the positions of the other parts can readily be understood by reference to Fig. 1. Fig. 3 is an end view of the pad-carrier. Fig. 4 is an edge view of the pad-carrier. Fig. 5 is a detail of the pad-elevating mechanism.

Similar figures of reference indicate similar parts throughout the views.

The machine has a central framework 1, from which at either end are extensions 2 3, on which are located the necessary appliances

for moving and supporting the platen 4. Such appliances being well known in the art, it is not deemed necessary to enter into any special description of them. The machine is provided with drums 5 6 7, whereon is placed abrasive material, preferably coarse, medium, and fine, in the order named. These drums are rotated in opposite directions, as indicated by the arrows, by a belt 8, common to all, which passes over their pulleys 9 10 11, intermediate pulleys 12 13, and is driven by pulley 14. These pulleys and drums are provided with suitable shafts 15 16 17 18 19 20 and bearings 21 22 23 24 25 26 therefor. Secured at each end of framework 1, at each side above platen 4, are guides 27 28, on which the pads 29 30 are carried for reciprocating movement parallel to platen 4 and the stock operated on.

Reference to Figs. 3, 4, 5 will best show the pad construction, wherein guides 27 28 are embraced by horizontal hubs 31 of considerable length. At the back of hubs 31 are formed vertical bosses 32 33, rising from a plate 34. On plate 34 and extending below it are vertical bosses 35 36, and through these bosses are rods 37 38, which support holders 39, under which the pads 29 30 are secured at each end by bolts 40. Through holders 39 are spring-rods 41, screw-threaded in the holders, passing freely through plates 34, and having heads 42, which enter pads 29 30, acting as means to support the pads from being displaced when doing their work of abrasion. Around rods 41, secured between plates 34 and holders 39, are springs 43, which permit the yielding of the pads 29 30. Lifters 44 and operated by pin 52 are provided for raising pads 29 30 clear of the stock to make them inoperative—as, for example, when the platen 4 is moving from A in the direction of the arrow with rough stock the pad would be lifted to allow the stock to first be operated upon by the drums, 5 rough, 6 medium, 7 smooth, and by pad 30 superfine, and upon the return movement of the platen pad 29 can be lowered to add its finish to that already produced by pad 30. The lifters comprise a plate 45, having hubs 46 47, embracing rods

37 38 and nuts 48 49, which regulate the tension on springs 43. Under hubs 31 and at right angles thereto are hubs 50, in which and reaching across the machine above pads 29 30 are shafts 51, which connect opposite hubs 50. At a point under plates 45 the shafts 51 are provided with pins 52, which in their inoperative positions, as seen in Figs. 3, 5, do not engage plates 45; but when shaft 10 51 is rotated to carry pins 52 upward they act as cams to raise plates 45, rods 37 38, holders 39, pads 29 30, and compress springs 43. As pins 52 reach a vertical position they enter notches 53, suspending the pads until 15 such time as the operator disengages them. The driving mechanism for reciprocating the pads are a pinion 54 on shaft 15 engaging a gear 55 on shaft 56, supported in bearings 57, together with pinions 58, also on shaft 56, 20 which engage gears 59 on shafts 60, supported in bearings 61 of frames 62, which are pivotally supported on shaft 56 at their outer end and at their inner ends by knuckle-pins 63 to lugs 64, attached to framework 1. Bosses 65 25 on gears 59 have crank-pins 66, and thereon are connecting-rods 67, which at their inner ends engage pins 68 in levers 69. The levers 69 are fulcrumed at 70 to bars 71, pivotally supported at 72 to framework 1. The upper 30 ends of levers 69 are secured to shaft 51, and all of these parts except pinion 54 and gear 55 are in duplicate at each side of the machine. In order to allow the upper ends of levers 35 69 to move in a straight line instead of an arc, their fulcrum 70 must move upward as the lever moves each way from its vertical central position to its extreme limit of motion, and this is permitted by pivots 72. This also causes the lower ends of levers 69 to 40 move in an irregular curve, due to the gradual raising of fulcrum 70. Connecting-rods 67 limit the movement of the lower ends of levers 69; but as pads 29 30 are free to move with the upper ends of the levers to 45 their limit the difference in movement between an arc from a fixed fulcrum and a straight line from a movable fulcrum is readily accomplished. Fulcrums 70 have guides 73, through which are passed rods 74, attached to arms 75 on shaft 51, and are the means employed to rotate the shaft and cause pins 52 to elevate lifters 44, which elevates the pad to its inoperative position, above and out of contact with the stock. Above guides 50 73 stops 76 are attached to rods 74, each being provided with a handle 77. The stops abut guides 73 when the pads are dropped to their operative position. Pad 30 is similarly equipped except that pivots 70' for its guides 78 are secured to supports 78, rigidly secured to framework 1. Pads 29 30 are connected for simultaneous movement by rods 79, secured to lugs 80 on hubs 31.

I claim—

65 1. In a sandpapering-machine, a frame-

work, a platen, multiple abrasive drums above the platen, and means for their rotation in opposite directions, and multiple abrasive pads exterior to the main framework, and adapted for reciprocative movements, and 70 means upon the machine for driving the first pad, and connections therefrom to the second pad for such movements.

2. In a sandpapering-machine, a framework, a platen, multiple abrasive drums above the platen, and means whereby the outer drums rotate in one direction while the center drum rotates oppositely, abrasive pads exterior to the drums, adapted for reciprocative movements before and after the stock 80 passes the rolls, means for such movements by mechanism on the machine, and means on each pad to independently place it into or out of operative abrasive position.

3. In a sandpapering-machine, a framework, a platen, multiple abrasive drums above the platen, and means for their rotation in opposite directions, abrasive pads having means on the machine for reciprocatory movement longitudinally of the machine for one 90 pad, with means for their connection so that the second pad shall be driven by the first, and means whereby one or both pads may be placed into operative or inoperative position independent of the other pad.

4. In a sandpapering-machine, a movable platen, abrasive drums above the platen, yielding and reciprocating abrasive pads also above the platen and connected for cooperative action, means to independently put a 100 pad out of abrasive position either during reciprocation or quiescence, means to rotate the drums, and independent means to reciprocate the pads, operated from the driving mechanism of the machine.

5. In a sandpapering-machine, a platen, abrasive drums above the platen, and means for their rotation in opposite directions, abrasive pads reaching across and above the platen, and means for their reciprocation 110 lengthwise of the platen, resilient means whereby the pads may press or yield toward the platen and to the stock being worked, and means to compress the resilient means and prevent contact with the stock aforesaid.

6. In a sandpapering-machine, a movable platen, abrasive drums above the platen and means for their rotation in opposite directions, abrasive pads guided parallel to the platen and reciprocated longitudinally of the 120 platen, levers for reciprocating the pads and driven from the machine, but separately from the drums, pivotally-supported fulcrums for the levers which permit the upper ends of the levers and their connections to the pads to 125 move in a line parallel with the platen's top, connecting-rods for the levers attached below their fulcrums and at the sides of the platen, and means for their driving.

7. In a sandpapering-machine, reciprocating

ing pads guided for movement in right lines, centrally - fulcrumed oscillating levers attached thereto which at their ends attached to the pads also move in right lines, movably supported fulcrums for the levers which permit the pad ends of the levers to move in right lines and their driven ends to rise and fall for such movement, and means to oscil-

late the levers from the machine independent of the movements for its other mechanisms. **10**

In testimony whereof I affix my signature in presence of two witnesses.
